(57) **CLAIM**

The ornamental design for an LED module, as shown and described.

DESCRIPTION

FIG. 1 is a perspective view of an LED module showing my new design;

FIG. 2 is a front side elevation thereof;

FIG. 3 is a rear side elevation thereof;

FIG. 4 is an end elevation thereof, it being understood that the view from both ends is identical; FIG. 5 is a top plan view thereof; and, FIG. 6 is a bottom plan view thereof.
